UNITED STATES PATENT OFFICE

2,109,310

WATER ICE AND DRY ICE REFRIGERATION
SYSTEMAlmon J. Cordrey, Chicago, Ill., assignor to The
Liquid Carbonic Corporation, Chicago, Ill., a
corporation of Delaware

Application July 3, 1936, Serial No. 88,716

10 Claims. (Cl. 62—91.5)

This invention relates to a refrigeration system utilizing both water ice and dry ice as cooling agents.

More specifically this invention relates to the refrigeration of storage spaces in trucks, trailers and the like vehicles by means of two different types of cooling agents, one of which serves to precool the storage space and is used when loading and at the start of a trip and the other of which is lighter and less bulky and is used to maintain the storage space in its cooled condition throughout the rest of the trip.

In my copending application Serial No. 87,881 filed June 29, 1936, entitled: "Dry ice refrigerating apparatus and method", I have described and claimed a dry ice refrigeration apparatus for vehicles having cold storage spaces. This apparatus includes an insulated container for dry ice, a heat exchanger and a liquid circulation system wherein a liquid having a low freezing point, such as alcohol, is circulated into thermal relation with the dry ice in the container to be cooled; the cooled liquid flows through the heat exchanger to absorb heat therefrom, and the warmed liquid from the heat exchanger recirculated back into thermal relation with the dry ice. The air of the storage space is circulated around the heat exchanger and cooled to maintain the storage space at a desired temperature. The air can be cooled to any desired amount by thermostatically regulating the flow of liquid through the heat exchanger.

According to the present invention a water ice bin or housing is formed either within the body of a truck, trailer or the like or on the roof of the vehicle or on a platform provided on the vehicle. Air from the storage space of the vehicle is circulated around the water ice in the bin, cooled by contact therewith and discharged back to the storage space. This circulation of air over the water ice serves to precool the storage space but due to the great weight of water ice required to maintain the storage space cooled, it is not desired to transport such a heavy cooling agent. Therefore a dry ice refrigerating apparatus, such as is described in my copending application, is used to maintain the precooled storage space cool along the route after the water ice has melted and drained from the vehicle.

It is thus not necessary, according to this invention, to transport a heavy cooling agent or to provide a large bin for such cooling agent since only enough water ice is used to precool the storage space and if desired to maintain the storage space cool along the first part of the trip.

Then, when the water ice has melted, the dry ice apparatus is automatically brought into operation.

It is then an object of this invention to provide a refrigerating apparatus for vehicles utilizing two different types of cooling agent, the heavier of which is discharged from the vehicle not later than during the first part of a journey.

A further object of this invention is to provide a combined water ice and dry ice refrigerating system for vehicles.

Another object of this invention is to provide, in combination with a transport vehicle for heat perishable goods, a bin for water ice having inlet and outlet communication with the storage space of the vehicle and a dry ice refrigerating apparatus including a liquid circulation system in said bin for maintaining the air of the storage space cool after the water ice has melted and been drained from the vehicle.

A specific object of this invention is to provide refrigerating apparatus in a transport vehicle for heat perishable goods including a bin for water ice, an inlet for air from the storage space to the bin, a discharge conduit for air from the bin back to the storage space and a dry ice refrigerating system including a heat exchanger in the discharge conduit for cooling air circulated through the duct after the water ice has melted.

Other and further objects of this invention will become apparent from the following detailed description of the annexed sheet of drawings which disclose a preferred embodiment of the invention.

On the drawing:

Figure 1 is a broken side elevational view, with parts broken away and shown in cross-section, of a truck trailer equipped with a refrigerating system according to this invention.

Figure 2 is a vertical cross-sectional view, with parts in elevation, taken substantially along the line II—II of Figure 1.

As shown on the drawing:

In Figures 1 and 2, the reference numeral 10 indicates a truck trailer of the usual type for transporting heat perishable goods, having an insulated roof 11 and insulated walls 12 defining a storage space 13 for the goods.

According to this invention a partition wall 14 is disposed in the storage space 13 near the front end thereof to define with the walls and roof of the storage space a bin 15 for water ice 16. The floor 17 of the bin 15 slopes to a drain 18 extending through the floor of the trailer for per-

mitting the drainage of melted ice from the bin.

An inlet opening 19 is provided through the wall 14 permitting the circulation of air in the storage space 13 into the bin 15. Movable louvers 20 may be disposed in the opening 19 to control the inlet capacity of the opening and to direct the incoming air over the ice 16 in the bin.

A duct 21 is provided in the lower part of the bin 15 and communicates with the space 22 between the floor 23 of the vehicle and a false bottom 24 within the storage space 13 of the vehicle. Discharge outlets 25 are provided at various points in the false bottom 24 to distribute cold air from the space 22 into the storage space 13, as will hereinafter be more fully pointed out.

The duct 21 has an opening 26 therein for receiving air circulated through the opening 19 into the bin. In order to prevent the clogging of the duct 21 with water ice 16, a shield 27 is disposed over the opening 26. This shield serves as a support for water ice 16 disposed over the opening 26 but is spaced from the opening so as to permit the free entrance of air into the duct.

A fan 28 is rotatably mounted in the duct 21 adjacent the opening 26 therein for propelling air through the duct and into the space 22 between the floor of the truck and the false bottom of the storage space. The fan can be conveniently driven by means of a small auxiliary engine 29 through a belt connection 30. Obviously, of course, an electric motor can be used to directly drive the fan.

An elongated container 31 is mounted within the bin 15 and preferably near the top thereof and can be conveniently supported from a wall 12 of the vehicle by means of a bracket 32. The container 31 houses a liquid receiving tank 33 (Figure 2) preferably formed of metal as is more fully disclosed in my copending application above referred to. Dry ice is disposed over the tank 33 in the housing 31 for cooling liquid within the tank.

A liquid having a low freezing point is placed in the tank 33 and flows from the tank through a pipe line 34 into the inlet header 35 of a heat exchanger 36 located in the duct 21 in front of the fan 28. The liquid then circulates upward through the tubes of the heat exchanger to cool these tubes and absorb heat from air flowing through the duct. The warmed liquid then flows upward by convection and by hydrostatic head of the liquid maintained above the heat exchanger into a discharge header 37 of the heat exchanger and from the discharge header into a pipe line 38 having a thermostatic valve 39 therein communicating with a pipe line 40 back to the inlet opening of the tank 33 which inlet opening is at a higher level than the discharge opening communicating with the pipe line 34.

The thermostatic valve 39 in the pipe line 38 can be adjusted to open at any desired temperature by means of an adjusting device 41 thereon.

The roof 11 of the vehicle 10 can be conveniently provided with a removable insulated cover 42 to permit a charging of the bin 15 with water ice 16. The container 31 also has a removable cover or door 43 in one end thereof to permit a charging of the container with dry ice.

The operation of the device is as follows:

Air from the storage space 13 of the trailer 10 enters into the bin 15 through the opening 19, circulates around the water ice 16 in the bin and is cooled by contact therewith. The cooled air then flows through the opening 26 into the duct

21 and from the duct 21 into the space 22 between the false bottom 24 of the storage space and the floor 23 of the trailer. This cold air is then distributed to the storage space 13 through discharge openings 25 provided in the false bottom 24.

As the water ice 16 melts, the water therefrom is drained from the trailer through the drain pipe 18.

When the cooling power of the water ice 16 diminishes below a point necessary to maintain the storage space at a desired temperature, air entering the opening 19 into the bin will be at a temperature higher than that desired. The thermostatic valve 39 can be set to open at any desired temperature and when the air contacting this valve is at a temperature above that for which the valve has been set, the valve will automatically open thereby permitting circulation of liquid through the heat exchanger 36. This liquid is cooled by dry ice in the container 31 and the heat exchanger 36 is thus cooled by the cooled liquid.

Air entering through the opening 26 into the duct 21 must pass around the heat exchanger 36 and be cooled by contact therewith.

The fan can be used to increase the circulation of air through the water ice bin 15 and duct 21. The dry ice in the container 31 will maintain the storage space 13 at a desired cooled temperature even after all of the water ice 16 has been melted and drained from the trailer.

Obviously many modifications of the above described apparatus are possible without departing from the scope of this invention. For example the circulation of air can be reversed so that the warm air enters the bin 15 at the bottom and the cold air is discharged at the top of the storage space 13. In another modification the fan and/or heat exchanger can be disposed at the inlet opening to the bin 15 instead of at the outlet opening.

The provision of a false bottom 24 in the storage space 15 makes possible a flat support for goods being transported in the storage space and also provides a good circulation of cooled air to all parts of the storage space. This false bottom need not be solid, but can be made of spaced slats thereby allowing the cooled air to circulate through the spaces between the slats and rise by convection to the top of the trailer. Obviously also a single duct or a series of ducts can be used to distribute the cooled air to the storage space 13.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In combination with a vehicle having a storage space therein, a bin carried by said vehicle and adapted to hold ice therein, means for circulating air from said storage space through said bin and back to the storage space, a dry ice refrigeration apparatus in said bin and means to bring said apparatus into operation when the air in the storage space is not maintained sufficiently cool by ice in the bin.

2. In combination with a vehicle having a storage space therein, an insulated bin carried by said vehicle adapted to hold water ice therein, said bin having an inlet for warm air from the storage space and an outlet for cooled air from

- the bin back to the storage space, a heat exchanger in the path of said air, a dry ice container in the bin, liquid receiving means in the container having inlet and outlet connections with the heat exchanger whereby a liquid is cooled by dry ice in the container, circulated through the heat exchanger to cool the same and is recirculated back into the receiving means and a thermostatic valve in the path of said liquid allowing said circulation only when the liquid in the bin has melted or does not have sufficient cooling power to maintain the air in the storage compartment at a desired temperature.
3. In combination with a vehicle having a storage space therein, an insulated bin carried by said vehicle adapted to hold water ice therein, said bin having an inlet for warm air from the storage space, a duct in said bin for conveying air therein for distribution to the storage space of the vehicle, a heat exchanger in said duct, a dry ice container in the bin, liquid receiving means in the container having inlet and outlet connection with the heat exchanger whereby a liquid is cooled by dry ice in the container, circulated through the heat exchanger to cool the same and is recirculated back to the receiving means and means for regulating the amount of said circulation.
4. In combination with a transport vehicle for heat perishable goods having a cold storage compartment, an insulated bin carried by said vehicle and adapted to hold water ice therein, a duct in said bin having an opening communicating with the interior thereof and an outlet opening communicating with the storage space of the vehicle, a heat exchanger in said duct, means for circulating a cooled liquid through said heat exchanger, means for propelling air thru the bin into the duct around the heat exchanger and back into the storage space of the vehicle and means controlled by the temperature in the bin for regulating circulation of the cooled liquid thru the heat exchanger.
5. In combination with a transport vehicle for heat perishable goods having a cold storage compartment, a partition wall in said cold storage compartment defining a bin adapted to hold water ice, and an inlet opening at the top of said partition wall, a duct in the bottom of said bin communicating with the storage space, said duct having an inlet opening therein, a heat exchanger in said duct, means for circulating a cooled liquid through said heat exchanger, a valve controlled by the temperature of the bin for regulating the flow of cooled liquid through the heat exchanger, and a fan in said duct for drawing air through said inlet over the water ice into the duct, around the heat exchanger and back to the storage space in a cooled condition.
6. A transport vehicle for heat perishable goods comprising means defining a storage space for said goods, a false bottom in said storage space having a plurality of openings extending therethrough, said false bottom being in spaced relation to the floor of said vehicle to define a passageway for air, a partition wall in said storage space at one end thereof defining a bin adapted to hold water ice, said partition wall having an inlet opening at the top thereof, a duct in the bottom of said bin having an inlet opening communicating with the bin and a discharge opening communicating with the space between the false bottom and floor of the vehicle, an insulated container in the top of said bin adapted to hold dry ice therein, a heat exchanger in said duct in fluid communication with the container, a fan adjacent said heat exchanger for propelling air to said duct and a motor for driving said fan.
7. In combination with a vehicle having a storage space therein, a bin carried by said vehicle adapted to receive water ice therein having air inlet and air outlet communication with the storage space, an insulated housing carried by said vehicle adapted to receive dry ice therein, a thermally conductive liquid container in said housing having liquid inlet and outlet openings, a heat exchanger in said bin in communication with the inlet and outlet openings of the liquid container for receiving cooled liquid therefrom and a valve controlled by the temperature in the storage space for regulating flow of liquid between the container and heat exchanger whereby dry ice is utilized to cool the storage space after the cooling capacity of the water ice is diminished beyond an amount necessary for maintaining the storage space below a predetermined temperature.
8. The method of refrigeration which comprises circulating air into thermal contact with water ice until the cooling capacity of the water ice diminishes beyond an amount necessary to maintain the air below a predetermined temperature and thereafter circulating a dry ice cooled liquid into thermal contact with the air to cool the air.
9. The method of refrigeration which comprises cooling a space below a predetermined temperature with water ice until the cooling capacity of the water ice decreases beyond the amount necessary to maintain the space below said temperature, utilizing the increased temperature of the space to induce the flow of a liquid cooled by a different agent into thermal communication with the space and thereafter cooling the space with said cooled liquid.
10. The method of refrigeration which comprises cooling a space below a predetermined temperature with water ice until the cooling capacity of the water ice decreases beyond the amount necessary to maintain the space below said temperature, cooling a non-freezing liquid with dry ice, utilizing the increased temperature of the space to induce the flow of the cooling liquid into thermal communication with the space and thereafter cooling the space with said cooled liquid.

ALMON J. CORDREY.
